UNITED STATES PATENT OFFICE

2,676,764

WEB WINDER

Walter E. Aulen, Newark, Del., assignor to Eddy-stone Machinery Company, Chester, Pa., a corporation of Pennsylvania

Application June 19, 1950, Serial No. 168,948

21 Claims. (Cl. 242—56)

1

The present invention relates to winding machines for web, commonly known as cloth winders, and to processes of winding web.

The present application is a continuation in part of my U. S. application Serial No. 40,967, filed July 27, 1948, for Web Winder, now abandoned.

A purpose of the invention is to secure more reliable and positive winding of more difficult web materials, such as the very heavy cloths, the plastic sheet materials and the plastic impregnated cloths which have been hard to wind, using standard equipment and techniques.

A further purpose is to facilitate the starting of the forward cut end of the web on a new shell by employing a moving belt or belts to carry the web around the shell and particularly over the upper rear portion of the shell.

A further purpose is to mount the threading belts on a transverse arm or arms.

A further purpose is to pivot the rocker support of the threading belts so that a stretch of belt to contact the shell initially has its forward upper end relatively above the shell and its lower rearward end relatively forward with respect to its support of the position it is to occupy in contact with the shell.

A further purpose is to spring urge the stretch of belt relatively upwardly with respect to the position it is to occupy in contact with the shell.

A further purpose is to resiliently tension the belts above and behind the point at which they contact the shell.

A further purpose is to grip the web at spaced points, desirably against the drums, by additional pressure while the web is progressing forward at the time of cutting.

A further purpose is to employ a brake desirably operating on the shaft for the rack gears of the pivot jaw support for the rear shell to exert downward force on the upper jaws, desirably applied through a spring.

A further purpose is to bring the brake into pressure-exerting position by lever interconnection with the transfer arms.

A further purpose is to hold the jaw arms pivotally supporting the roll and the forward shell down by pressure desirably exerted through thrustors at the time of cutting, the thrustors preferably being operated automatically by movement of the transfer arms into position to bring the threading mechanism against the rear shell.

A further purpose is to bring in the new or rear shell on rearwardly and downwardly directed runners extending to the jaw pivot supports, and

2

desirably to provide for latching of a shell on the runners by a latch operated from the transfer arms.

A further purpose is to provide tracks for carrying the pivots of the rear shell to the forward drum.

A further purpose is to raise the jaw arms automatically as by thrustors when the knife lowers, to remove the roll from the machine.

A further purpose is to move the jaw arms downwardly automatically as by thrustors when the rear shell is moved forwardly to the forward drum.

A further purpose is to provide release jaws on the jaw arms which are opened desirably by fluid cylinders and which are preferably locked closed by cams at the jaws.

Further purposes appear in the specifications and in the claims.

In the drawings I have chosen to illustrate one only of the numerous embodiments in which my invention may appear, choosing the forms shown from the standpoints of convenience in illustration, satisfactory operation and clear demonstration of the principles involved.

Figures 1 to 10 inclusive are diagrammatic position views looking from the end, showing the steps in the operation.

Figure 11 is an end elevation, partly in section, of the preferred machine embodying the invention.

Figure 11a is a fragmentary sectional elevation showing the notched wheel and pawl, sectioning away the remaining structure.

Figure 12 is a top plan view of Figure 11, broken at the center to eliminate the intermediate portions of the lengths of the drums and shell.

Figure 13 is a fragmentary end elevation, showing the interconnection between the transfer arms and the latches.

Figure 27 is a view corresponding to Figure 24, showing the jaw open.

In the prior art, winding machines for web, commonly known as cloth winders, have found their greatest application in the winding of standard woven cloth of comparatively light weight and having normal handling characteristics. The operation of the machine to transfer shells and rolls has been largely accomplished by hand. With the heavier weights of material and particularly with materials having markedly different handling properties, such as plastics (for example polyvinyl chloride, polyvinyl acetate, polyvinyl chloride-acetate, cellulose acetate, cellulose butyrate, cellulose acetate butyrate, ethyl cellulose, methyl cellulose, rubber, synthetic rubber and the like, as well as the plastic-impregnated woven materials), it has been found quite difficult to cut the materials, and in many instances manual manipulation of the shells and rolls from one position to another has been tedious, expensive from a labor standpoint and even dangerous. Serious accidents, injurious to workers, have resulted when rolls have gotten out of control, falling from the machine or rolling forward unexpectedly. The difficulties and hazards involved will be appreciated when it is understood that the weights involved in a single roll are in some cases measured not in hundreds of pounds but in tons.

The difficulties of handling are increased by the fact that in the older practice cloth commonly could be made to adhere to a new shell by moistening, whereas many of the newer materials do not have improved adherence when moistened, and moistening is harmful or destructive to some of the webs which are wound.

In accordance with the present invention, the threading of the forward cut end is accomplished in a much more positive manner by carrying the forward cut end around the new shell under the action of moving belts. It has been discovered that part of the difficulty with threading and also with cutting was that an undue amount of slack was created during the cutting operation, on account of the fact that before cutting the web the knife carried the web upward to a considerable distance above its normal position, thus creating a large amount of slack material at the forward cut end by the time the cutting was completed. To overcome this the forwardly moving web is gripped, preferably on both sides of the position of cutting, at the time of cutting to hold the web taut. The cutting is accomplished automatically in response to the movement of the threading mechanism into position. The downward motion of the knife at the completion of the cutting also controls the release of the completed

roll from the machine so that delay and labor are avoided.

The insertion into the machine of a new shell no longer involves the danger of manipulating the shell above the moving web from the side, since runners are provided and cooperating latches are employed to guide the new shell into the rear position. Likewise the difficulty formerly encountered in carrying the shell and partially completed roll over the gap between the rear and forward drums is avoided by providing a track to carry the shell pivot across this gap, and providing automatic mechanism to lower the jaw arms to receive the shell pivots.

The jaw-arms have opening jaws which release the roll without the need to shift the jaw arms by hand.

Understanding of the operation of the device will be aided by considering Figures 1 to 10 inclusive before examining the machine in detail.

The web 30 is passing in the direction of the arrow from any suitable source, which may, of course, be a production line, but here is shown as an unwinding roll 31.

The machine includes a front drum 32 and a rear drum 33 which, as in usual practice, are put side by side at the same height and preferably horizontal and parallel, with a slight space or gap between. The drums are intended to turn in the direction of the arrows (clockwise in Figures 1 to 10).

Between the drums is located a gate 34, normally positioned below the top of the drums, but capable of rising above them and carrying at the upper end a knife 35, running longitudinally. The gate is guided for motion upwardly and downwardly as well known.

The web 30 is wound on a shell 36, which at the beginning of the winding, as shown in Figure 1, is designated as a new shell 36' until it is shifted to the forward drum, when it receives the designation 36² to distinguish from the new shell which is later added for the next roll.

In the position of Figure 1, the web is winding on the shell 36', which is resting on and idling with the rear drum 33. It is assumed that at this point the web has just been cut and the forward cut end has just been threaded around the new shell 36', while the old shell and the roll wound thereon have been removed.

Transfer arms 37 are in their rear position about their pivot shaft 38 above the drums and carry at their lower ends supports 40, on which are mounted belt threading devices 41.

As seen in Figure 2, the shell 36¹ winds on the rear drum 33 until the roll 42 increases to a substantial size, at which point the shell and the winding roll are transferred to the forward drum, as shown in Figure 3, under the forward pressure of the transfer arms 37, engaging the back of the roll. The web in this position travels across at 43 between the drums to the forward drum. From the position on top of the forward drum, the roll 42 rolls forward until the pivots 44 on the ends of the shell 36² engage in the jaws 45 of the jaw-arms 46, pivoted at 47 as well known.

The size of the roll continues to build up on the shell 36², supported by the jaw arms and contacting the forward drum, until the web is cut as shown in Figure 8.

Runways 48 at opposite ends of the machine, extend rearwardly and downwardly from a position above the roll when it is of the size shown in Figure 4 to receive a new shell 36¹, whose pivots

5

are resting on the runway and held against premature downward movement by latches 50, pivoted at 51 above the runways.

The latches 50 are rigidly mounted on pivot shaft 51, and the shaft 51 carries at its end a crank 52, which pivotally connects at 53 with a link 54 (see also Figures 13 and 14). Link 54 pivotally connects at 55 to a crank 56 on the shaft 38, which pivots the transfer arms. In this way the latches are made to move in unison with the transfer arms.

Between the positions of Figures 4 and 5, the transfer arms and the latches are moved rearwardly permitting the new shell 36¹ to move down the raceways 48 and, since the pivot 51 of the latches is closer to the raceway at the top than at the bottom, the pivots of the shell 36¹ are released by the latches and the shell 36¹ engages in the pivot jaws in position above the rear drum. Also, as well known in the art, once the pivots of the shell engage in the pivot jaws and the jaws are moved down, the shell 36¹ moves down until it contacts the web on the upper side of the rear drum 33 and idles with the web as indicated by the arrow in Figure 6.

Between the position of Figures 6 and 7, the roll on the forward drum continues to increase in size until it is wound to the full size. At this point the transfer arms are moved forward until the new shell 36¹ is contacted by belts of the belt threading device 41, and at the same position the pressure against the forward and rear drums above the web is desirably increased as later explained, to hold the web stretched taut at 43. The knife then moves upward into contact with the web and cuts the web as shown in Figure 8, at the same time desirably directing the new forward edge 57 of the web upward and around the new shell 36¹ as well known and later described.

As the forward edge 57 travels around the new shell, it comes in under the belts of the belt threading device 41, which are travelling with the periphery of the new shell on the upper rear portion thereof. This assures wrapping of the cut end around the new shell to start the new roll. As indicated in Figure 9, while the winding continues on the new shell and the transfer arms and belts are in the position in which the belts continue to contact the roll which is beginning to wind, the jaw arms 46, preferably automatically, as later explained, are pushed upwardly to release the shell 36² of the completed roll and allow the completed roll to drop on loading mechanism 58, where it may be carried to a transfer car 60. At any conveniently earlier point, desirably between Figures 8 and 9, the knife moves downwardly to its inactive position. Since the jaw arms have released the roll 42, which has been completed, they are desirably moved downwardly to the position shown in Figure 10, to receive the new roll when it is wound to the stage shown in Figure 4.

Having considered the diagrammatic views of Figures 1 to 10, the mechanism of Figures 11 to 23 will be taken up to illustrate the structure in more detail.

The machine comprises a frame 62 and standards 63 extending above the same. The frame has journals 64 on which the drums are mounted and rotate, the drums being suitably driven by gearing 65¹ and intergeared by chain and sprocket mechanism 65 at one end. The journals 64 and the pivots on the shell serve as pivot mountings for the roll. The standards 63 have guideways 66 for spring urged pivot jaws 67, 75

6

which hold the pivots 44 on the new shell 36¹ as well known in the art. The upper pivot jaws 67 (Figure 18) are connected with racks 68, which extend vertically in the guideways 66. The downwardly directed pivot jaws are spring urged downwardly by springs not shown. The racks at each end intermesh with the gears 70 on a cross shaft 71, provided with the usual end wheel 72 and hand brake 73 (Figure 11) at one end of the machine. The cross shaft 71 is journaled in the standards in any suitable manner as well known.

The transfer arms 37 are on the transfer shaft 38, which is journaled at 74 on the standards, and each of the several transfer arms is suitably provided with a pair of belt threading devices 41 on a support 40, extending rearwardly from the ends of the transfer arms. As best seen in Figure 15, each belt threading device is supported on a rocker support 75 of generally triangular shape pivoted to the support 40 at 76 making a pivot mounting for the rollers (Figure 15), near its upper rearward corner and urged upwardly at its upper forward end, and forwardly at its lower end by a tension spring 77 connecting to the support between suitable abutments. Thus the tendency is to raise the forward end of the belt threading device into a position above the shell, and the lower end to a relative forward position whenever the belts are out of contact with the shell.

An endless belt 78 turns on an upper forward roller 80, a lower rearward roller 81 and an upper rearward roller 82, making a triangular path. With respect to the rocker support 75, the rollers 80 and 81 have stationary axes, but the roller 82 is supported at the outer end of a belt tensioning arm 83, pivoted on the axis of roller 81, and urged toward the rear from the support by a spring 84 between suitable abutments (Figure 15).

On one of the tensioning rockers 83 is an upward switch operating extension 85 (Figure 11), which closes an electric switch 86 whenever the belts contact the rear shell and urge the tensioning roll 82 forward. The switch 86 when closed actuates valve-operating solenoid 87 (Figure 20) (in series with a normally closed switch 88 in closed position and the normally closed side 90 of a double throw switch 91), opening a valve 92 to apply high pressure fluid (such as compressed air) through a pipe 93 (Figure 11) to the lower end of a cylinder 94, having a piston not shown, whose rod is operatively fastened to a gate 34, carrying the knife 35, suitably consisting of diagonally disposed rearwardly directed teeth. Thus when the solenoid 87 is energized the high pressure fluid raises the knife carrying gate to a position as shown in Figure 15, cutting the web. As well known in the art, the gate has below the knife, extending across the machine, a finger shaft 95, carrying fingers 96, which tend to spring to a position engaging the top of the new shell under the action of spiral spring 97, and in such position tend to deflect the forward cut end of the web around the shell. In lower position of the gate, the fingers are forced into a vertical position by a finger cam 98 (Figure 11).

The valve 92 when restored to normal position allows the lower end of the cylinder 94 to exhaust and applies restoring pressure to the top of the cylinder as well known. When the valve shifts to the position to raise the gate, the restoring pressure is cut off from the top of the cylinder, which is exhausted.

At the time the gate is raised for cutting, it is

desirable to hold the web taut against the two drums. As far as the rear drum is concerned, this is accomplished by pressing downward at this time on the racks and pivot jaws of the new shell, so as to force the new shell tightly against the web on the rear drum. The cross shaft 71 has at one end, keyed thereon, a brake drum 100, which is surrounded by a brake band 101 having friction material 102 (Figures 16 to 18). Loose on the shaft 71 on both sides of the brake drum are levers 103, which at their outer ends carry a pivot 104. The levers 103 are thus capable of moving with respect to the shaft 71 on which they pivot. On the pivot 104, at the ends of the levers, is pivotally supported a brake lever 105, having one end of the brake band 101 secured thereto at 106 between the shaft 71 and the pivot 104, and the other end (the one that extends over the top of the brake drum) secured to the brake lever 105 at 107 outwardly of the pivot 104 with respect to the shaft 71. Thus downward pulling on the end of the brake lever will lock the brake and upward positioning will release the brake, and downward pulling after the brake locks will rotate the shaft 71 in a direction to exert torque on the gears 70 and force the racks 68 and jaws 67 downwardly to force the new shell 36' downwardly.

The outer end of the brake lever 105 is normally urged downwardly by a tension spring 108 from a spring abutment 109 on one standard. Likewise the end of the brake lever toward the shaft 71 with respect to the pivot 104 is upwardly urged by tension spring 110 from the standard 63. The levers 103 are limited in upward motion by an adjustable stop 111 on the standard, which engages the lever on the side toward the standard.

The transfer arm shaft 38 carries at one end a crank 112 fixed thereon, which makes pivotal connection at 113 with toggle links 114, making pin and slot connection at 115 with the brake lever 105. Thus when the transfer arms move to the rear, the effect of the toggle (consisting of the crank 112 and lever 114) is to release the brake, thus relaxing pressure on the pivot jaws. At the other positions of the transfer arms, the spring 108 applies extra downward pressure on the pivot jaws and on any shell on the back drum. If no shell is on the back drum, the upper jaws are desirably held in upper position by engaging notched wheel 71' on cross shaft 71 by pivoted pawl 71² (Figures 11 and 11a). The slot at 115 is long enough to permit the transfer arms to move to the forward position of Figure 3. When the crank 112 moves to the position corresponding to rearward limiting travel of the transfer arms, the switch 88 (Figures 16 to 20) which is normally closed, is opened by contact with the crank 112, thus cutting off current from the solenoid valves 116 (Figure 11) and 117 (Figure 20), which admit fluid pressure as by a hose to the upper ends of thrust or cylinders 118 containing piston and rod combinations 120. The valves 116 and 117 automatically exhaust when they are not open to admit fluid pressure, as well known. The cylinders are pivoted on the frame at their lower ends 121 and at their upper ends are pivotally connected at 122 to the respective jaw arms 46.

In the preferred embodiment as best seen in Figures 24 to 27, the jaw 45 has an openable jaw portion 119 at the lower forward end which is pivoted at 119² to the jaw arm 46, and is opened by a link 119² secured to the openable jaw portion 119 at 119³ and pivotally connected at 122 to the

rod of the piston and rod combination 120. The lever 119² is urged by tension spring 119⁵ from the jaw arm in the direction to close the openable jaw portion.

On the stationary part of each jaw there is rigidly mounted at the back in Figure 24 a cam 119⁶ (Figure 26^a) which has a recess 119⁷ and a track 119⁸. The pivot 122 between the piston rod 120 and the link 119² carries a roller 119⁹ which rides the cam 119⁶. The downward motion of the jaw arms is limited by adjustable stops 46' which engage abutments on the frame.

When fluid pressure is admitted to the lower ends of cylinders 118 the piston and rod combinations 120 push up, causing cam rollers 119⁹ to leave cam recesses 119⁷ and move to the right in Figure 26^a along tracks 119⁸, pushing the links 119² to the right in Figures 26^a and 27 to open movable jaw portions 119. The wound roll then drops out of the jaws.

When the upward pressure on the piston and rod combinations 120 is released, the jaw portions 119 close under the action of springs 119⁵ which pull rollers 119⁹ into cam recesses 119⁷ and lock the jaw portions 119 in closed position. The jaw arms then drop under their own weight. At the time of cutting, pressure is applied to the tops of piston and rod combinations 120 to apply additional pressure on the forward roll.

When the gate moves downward as shown in Figure 9, an operator 123 passes by and momentarily shifts switch 91 (Figures 22, 23) moving it from the position 90 (closing the circuit in series with the switch 88, Figure 20), to a new position, 35 closing the contacts 124 and energizing solenoid valves 125 and 126 which momentarily apply fluid pressure to the bottoms of cylinders 118 to urge the jaw arms or the movable portions upward for the purpose of releasing the roll. The jaw arms tend to drop by gravity when the front roll is removed. The valves 116, 117, 125 and 126 are of the well known type which automatically exhaust the ends of the cylinders when not open to admit fluid pressure. The operator 123 does not move the switch 91 from the normal position 90 on upward movement of the gate due to the fact that the operator is pivoted at 127 and yields under the action of a tension spring 128 on upward movement, but on downward movement is held in the position shown by a stop 129. The switch 91 is too stiff to be deflected to close on the upward stroke.

It should be noted that when a roll from the back drum is to enter the jaw arms, the jaw arms are down, and the application of fluid pressure to the tops of cylinders 118 will desirably assure that the jaw arms are in lower position and that their openable portions are closed. The pivots of the shell in moving forward enter the jaws 45 from the back, between jaw sides 45' and 45² (Figure 24).

The shaft 38 and the transfer arms and belt threading devices are conveniently manipulated from the end of the machine by a handle 131 (Figures 11, 13 and 14) on a crank arm 132 on the shaft 38. A latch 133 is desirably pivoted at 134 and has a latching grip 135 within the reach of the operator. The opposite end of the latch engages a latching plunger 136 to permit withdrawing the plunger from a latching recess 137 on the standard when the latching grip is engaged. The latching plunger acts against compression spring 138.

In the prior practice, when the shell has been transferred from the rear to the forward drum,

it has tended to drop into the space at 43 between the drums. To overcome this a track 140 (Figure 11) is provided at each end, extending across this space so as to carry the shell pivots from one drum to the next.

As indicated in Figure 20, an alarm device 141 is provided with operating switches 142 and 143 (Figure 11) in parallel. The switch, 142 by its operating arm 142', engages the roll on the forward drum and sounds the alarm when the roll reaches a predetermined size for completion. The switch 143, by its operating arm 143' as shown in Figure 21, engages a dog 144 on one upper jaw when the pivot jaws rise to a predetermined level, indicating that the new shell on the back drum has reached a desired size.

The circuit of Figure 20 connects switches 86 and 88 in series, so that switch 86 will not operate to raise the knife in case it is carelessly manipulated by someone adjusting the shells at a time when switch 88 is open because the transfer arms are in their rear position.

Contacts 99 of switch 91 are connected in series with switches 88 and 86 when all switches are closed, and these switches are in series with solenoid 87 across the line. Contacts 124 of switch 91 are in series across the line with the two parallel branches in which solenoid valves 125 and 126 are placed. Normally closed switch 88 is in series across the line with the two parallel branches in which solenoid valves 116 and 117 are placed.

Switch 91 is a two circuit limit switch used to energize solenoids 125 and 126. As the gate is coming down to its original position after the cutting operation, the operator 123 fastened to the gate (Figure 22) momentarily contacts the actuating arm of switch 91 (Figure 23), thereby opening the circuit to switch 88 and closing the circuit to solenoids 125 and 126 which will deenergize solenoids of valves 116 and 117 and energize solenoids of valves 125 and 126 which apply fluid pressure to the bottom of cylinder 118 to urge the jaw arms or the movable portions upward for the purpose of releasing the rolls. After operator 123 completes its cycle, switch 91 returns to its normal position as shown at 90 on Figure 20, closing the circuit to switch 88. Switch 88 is a normally closed limit switch actuated by lever 112 (Figure 11) and when closed used to energize the solenoids of valves 116 and 117 and to complete a circuit to switch 86. The source may be alternating or direct current as desired.

In operation of the device of Figures 11 to 23 it will be understood that in Figure 1 with the transfer arm vertical, switch 88 will be open and the jaw arms 46 will not be under pressure. In Figure 2, when the transfer arm moves clear back switch 88 remains open and valves 116 and 117 remain closed and connected to exhaust and pressure is off the top and bottom of the jaw arm cylinders while the shell on the back roll increases in size. As the roll increases in size when it is being wound on the rear drum it raises the pivot jaws and thereby causes shaft 71 to turn through the rack and gears. When the roll is wound to a predetermined diameter to be transferred from the rear to the front drum, the pawl 71' drops into a notch of notched wheel 71' and causes the pivot jaws to be held in raised position, thereby also preventing shaft 71 from turning when the roll leaves the rear drum. When the transfer arms push the new shell and roll on to the front drum in Figure 3, and on to the jaw arms in Figure 4, switch 88 is again closed, and

pressure is again applied to the tops of the jaw arm cylinders, holding them down in position to receive the shell in Figure 4.

When the transfer arms are moved back to the position shown in Figures 5, 6 and 7, switch 88 is again opened and pressure is taken off the tops of the jaw arm cylinders as the jaw arms move up when the roll increases. Latches 59 move back with the transfer arm and release the new shell. In Figure 8, for the first time in the cycle, the belts are moved by the machine operator to contact the new shell which has been applied in Figures 4 to 7, closing switch 86 and applying pressure through solenoid valve 87 to the bottom of the gate cylinder. This causes the gate and knife to rise in Figure 8 at the same time downward pressure is applied on the new shell. As soon as the transfer arms are moved back in Figure 9, switch 86 opens under its spring action and the gate moves down under the pressure normally applied to the top of the gate cylinder. On the way down, however, the gate moves switch 91 to close contacts 124 momentarily and this momentarily opens valves 125 and 126 to apply fluid pressure to the bottoms of the jaw arm cylinders to release the roll 42 as shown in Figures 9 and 10.

It will be evident that by the present invention the difficulties in handling very large rolls and very thick materials and the labor and hazards to the workmen are greatly decreased.

It will be evident that by the present invention the threading of difficult materials around a new shell is greatly facilitated so that the machine can operate successfully on very thick and very stiff materials and on materials whose surface characteristics are markedly different from ordinary cloth. Also, even when operating on ordinary cloth the chance of error in starting the roll on the new shell is greatly reduced.

In accordance with the invention, it will be evident that the cutting by the knife is made much more positive, since the web is held down on both sides of the line of cutting. Cutting is made automatic in response to the movement of the threading mechanism in position.

The manipulation of the jaw arms to receive the partially wound roll, as well as to discharge the fully wound roll, is also made automatic and manual operating is unnecessary.

The tendency of the shell and partially wound roll to drop in the space between the rear and the forward drums and in that case to bounce off the machine, and the necessity to exert force to lift the roll out of this space, are avoided, carrying the shell pivot across the space on the level of its position when the shell and partially completed roll engage the top of the rear drum.

The necessity of reaching over the moving web to insert the new shell is also avoided, since, in accordance with the invention, the new shell is carried in from the front on top of the roll which is being wound.

In view of my invention and disclosure variations and modifications to meet individual whim or particular need will doubtless become evident to others skilled in the art, to obtain all or part of the benefits of my invention without copying the process and structure shown, and I, therefore, claim all such insofar as they fall within the reasonable spirit and scope of my claims.

Having thus described my invention, what I claim as new and desire to secure by Letters Patent is:

1. In a cloth winder, a pair of spaced parallel

11

drums, means for turning the drums in the same direction, means for supporting a forward shell in rotatable position while the web is wound thereon and while the outer circumference of the roll being wound and the forward shell are idling with the forward drum, a rear shell positioned in contact with the web above the rear drum and idling with the rear drum, pivot means for supporting the rear shell, a knife, means carried by the knife for cutting the web between the drums and reversing the direction of the cut end to make it travel over and around the rear shell, pivoted transfer arms adapted to move the rear shell to the forward drum when it has been sufficiently wound and belt mechanism supported on the transfer arms and in one position of the transfer arms engaging the upper rearward portion of the rear shell and moving in the direction of motion of the adjoining portion of the circumference of the rear shell, thereby aiding in carrying the forward cut edge of the web around the rear shell.

2. In a cloth winding machine, a pair of spaced parallel drums, means for turning the drums in the same direction, a forward shell, means for supporting the forward shell in rotatable position while the web is wound thereon and while the outer circumference of the roll being wound and the forward shell are idling with the forward drum, a rear shell positioned in contact with the web above the rear drum and idling with the rear drum, pivot means for supporting the rear shell, knife means and means carried by the knife for cutting the web between the drums and reversing the direction of the cut end to make it travel over and around the rear shell, pivoted transfer arms adapted to move the rear shell to the forward drum when it has been sufficiently wound and belt mechanism supported on the transfer arms and in one position of the transfer arms engaging the upper rearward portion of the rear shell and moving in the direction of motion of the adjoining portion of the circumference of the rear shell, thereby aiding in carrying the forward cut edge of the web around the rear shell, the belt mechanism comprising an endless belt, rollers supporting the belt, tension means for urging one of the rollers to a position to tension the belt, and a pivot mounting for the rollers on one of the transfer arms located rearwardly of the rear shell.

3. In a cloth winding machine, a shell on which a web is about to be wound, a support adapted to move to a position adjoining the shell, an endless belt having a forwardly directed stretch adapted to contact the shell and the web when wound thereon, rollers supporting the belt, tension means for urging one of the rollers to a position to tension the belt, a pivot mounting for the rollers on the support located rearwardly of the forward stretch of the belt, and spring means urging the upper portion of the forward stretch of the belt upwardly and the lower portion of the forward stretch of the belt forwardly with respect to the position occupied when in contact with the shell.

4. In a winding machine for webs, a shell having rotatable pivot support, a support for a threading mechanism, a belt rocker pivotally connected to the support and extending forwardly of the pivot point toward the shell, spring means for urging the upper forward end of the belt rocker upwardly, an upper forward and a lower rearward belt roller pivotally mounted on the belt rocker, a tension arm pivotally mounted

12

on the belt rocker and extending from a lower position to an upper rear position, a tension roller pivotally mounted on the tension arm at the upper rear position, spring means urging the tension roller away from the upper forward roller and a belt around the rollers.

5. In a machine for winding a web, a pair of spaced parallel horizontal drums, means for driving the drums in the same direction, means for progressing a web across the upper surfaces of both drums, means for pivotally supporting a forward shell while rolling up the web thereon with the outer circumference of the roll in contact with the forward drum, and the roll and forward shell idling with the forward drum, means for pivotally supporting a rearward shell above and in contact with the web at a position where it contacts the rear drum, knife means adapted to move upwardly between the drums and cut the web, rack and gear mechanism connected to the pivot for the rear shell, a brake drum on the rack and gear mechanism, a brake band on the drum, a brake lever connected to the band, a spring urging the lever to a position to supply pressure on the shell, and lever mechanism for releasing the spring to apply the spring pressure at the time of cutting.

6. In a machine for winding a web, a pair of spaced parallel horizontal drums, means for driving the drums in the same direction, means for progressing a web across the upper surfaces of both drums, means for pivotally supporting a forward shell while rolling up the web thereon with the outer circumference of the roll in contact with the forward drum, and the roll and forward shell idling with the forward drum, means for pivotally supporting a rearward shell above and in contact with the web at a position where it contacts the rear drum, knife means adapted to move upwardly between the drums and cut the web, rack and gear mechanism connected to the pivots of the rear shell, a brake drum on the rack and gear mechanism, a brake band on the brake drum, a brake lever connected to the brake band and adapted to apply it and to cause rotation of the brake drum, a spring urging the brake lever toward the position for applying additional pressure to the rear shell, transfer arms pivotally supported above the rear shell in a position to contact the same, belt threading devices on the transfer arms adapted to contact the rear shell, and lever mechanism connecting the transfer arms to the brake lever to permit the spring to apply pressure to the shell pivots when the belt threading devices engage the shell.

7. In a winding machine for a web, a pair of spaced horizontal parallel drums, means for rotating the drums in the same direction, means for carrying a web across the drums, a pivotal support for a forward shell and for a roll of web winding thereon supported above and idling with the forward drum, a forward shell, knife means for cutting the web between the drums, a rearward shell in contact with the web at a point where it is extending over the rear drum, and idling with the rear drum, a belt threading device engaging the circumference of the rear shell and automatic means set in motion by the engagement of the belt threading device with the rear shell for raising the knife.

8. In a winding machine for a web, a pair of spaced horizontal parallel drums, means for driving the drums in the same direction, jaw supports above the rear drum adapted to pivotally

support a shell, runways extending downwardly and rearwardly to the jaw supports, latches pivoted above the runways and adapted to move from a position in which the latches can hold the pivots of a shell in the runways to a position at which the shell pivots are released, transfer arms for moving a shell from the rear to the forward drum and levers interconnecting the transfer arms and the latches.

9. In a winder for a web, a pair of spaced parallel horizontal drums, means for rotating the drums in the same direction, a shell having pivots and idling with one of the drums, pivotal jaw supports for the shell, transfer arms pivoted above the shell and adapted to move it from one drum to the other and tracks extending across the space between the drums to carry the pivots over the space.

10. In a winding machine for a web, a pair of spaced parallel horizontal drums, means for driving the drums in the same direction, pivoted jaw arms cooperating with the forward drum to support a shell thereon, pivoted transfer arms for moving a shell from the rear to the forward drum and means including a thruster operated by the forward motion of the transfer arms for moving the jaw arms downwardly before the shell is transferred to the forward drum.

11. In a machine for winding a web, a pair of spaced parallel horizontal drums, means for pivotally supporting the drums, means for driving the drums in the same direction, means for pivotally supporting a forward shell in idling contact with the forward drum and above the forward drum, means for pivotally supporting a rearward shell in idling contact with the rear drum and in some cases with a web moving over the rear drum, a knife normally positioned between the drums beneath the path of a web travelling across the drums, means for reciprocating the knife upwardly into the path of the web, a resilient clamp operative on the means for pivotally supporting the rearward shell to urge the rearward shell downward from the pivotal support, acting in supplement of any pressure applied by the weight of the parts, and means for applying the resilient clamp pressure on the pivotal supporting means only at the time of cutting.

12. In a machine for winding a web, a pair of spaced parallel horizontal drums, means for driving the drums in the same direction, means for pivotally supporting a forward shell in idling relation with the circumference of the forward drum and in some cases with a web riding on the forward drum, means for pivotally supporting a rearward shell in idling relation with the rear drum and in some cases with the web riding on the rear drum, a knife positioned between the drums and normally below the path of a web extending across between the drums, means for reciprocating the knife up into the path of the web for cutting the web, means for pushing downward across the forward drum on the means for pivotally supporting the forward shell, and means for actuating the means for pushing downward at a time including the time at which the knife is raised.

13. In a machine for winding a web, a pair of spaced parallel horizontal drums, means for driving the drums in the same direction, pivoted jaw arms extending out above the forward drum at either end thereof adapted to support the pivots of a forward shell idling on the forward drum, means for pivotally supporting a rearward shell

above and in contact with the web at a position where it contacts the rear drum to idle thereon, a knife between the drums normally positioned below the web, means for reciprocating the knife upward into the path of the web, fluid pistons operatively connected to the jaw arms for urging the jaw arms downward and urging the forward shell against the forward drum, and means operative at a time including the time of cutting for energizing the fluid pistons.

14. In a machine for winding a web, a pair of spaced parallel horizontal drums, means for driving the drums in the same direction, pivoted jaw arms extending out above the forward drum for

15 pivotally supporting a forward shell idling with the forward drum, means for pivotally supporting a rearward shell above and in contact with the web at a position where it contacts the rear drum so that the rearward shell idles with the

20 rear drum, a knife positioned between the drums and normally beneath a web traveling across between the drums, means for applying downward pressure supplemental to that exerted by the weight of the parts on the jaw arms, means for

25 actuating the means for applying the downward pressure on the jaw arms at the time of cutting, means for applying supplemental pressure in addition to that applied to the weight of the parts on the means for pivotally supporting the rearward shell and means operative to the time of cutting for energizing the means for applying supplemental downward pressure on the means for pivotally supporting the rearward shell.

30 15. In a winding machine for a web, a pair of spaced horizontal parallel drums, means for driving the drums in the same direction, jaw supports above the rear drum adapted to pivotally support a shell, runways extending downwardly and rearwardly to the jaw supports, latches pivotally extending into the runways and adapted to engage and hold the pivots of a shell, the latches moving to a position out of contact with the pivots of a shell, transfer arms for moving a shell from the rear to the forward drum, and a shell having its pivots resting in the runways and held by the latches.

35 16. In a winder for a web, a drum adapted to turn, a shell having pivots for winding a roll of web idling with the drum, jaw arms pivotally supporting the shell and roll positioned above the drum, latch means on the jaw arms for releasing the pivots of the shell and fluid mechanism operatively connected to the latch means to release the latch means and concurrently raise the jaw arms.

40 17. In a winder for a web, a drum adapted to turn, a shell for winding a roll of web idling with the drum and having pivots, jaw arms pivotally supporting the shell and roll and engaging the pivots of the shell, a gate extending longitudinally of and behind the drum and reciprocable vertically, a knife mounted on the gate extending longitudinally of and behind the drum for cutting the web before it reaches the roll, latch means on the jaw arms for releasing the pivots of the shell, thruster means operatively connected to the jaw arms and to the latch means for releasing the latch means and raising the jaw arms and automatic mechanism operated by the gate to energize the thruster means.

45 18. In a machine for winding a web, a pair of spaced parallel horizontal drums, means for pivotally supporting an idling shell resting upon one of the drums to wind a web on that drum, means for pivotally supporting an idling shell

transferred to the other drum and resting upon the same to wind a web on the other drum, a knife normally positioned below the web and between the drums, means for reciprocating the knife upward into engagement with the web as it is progressed, means for applying pressure additional to the pressure applied by the weight of the parts to shells idling on both of the drums, means for actuating the means for applying additional pressure to the shell on the forward drum prior to raising the knife and automatic means coordinated with the raising of the knife for actuating the means for applying additional pressure to the shell on the rear drum.

19. In a machine for winding a web, a pair of spaced parallel horizontal drums, means for driving the drums in the same direction, means for pivotally supporting a forward shell idling above and in cooperation with the surface of the forward drum, means for pivotally supporting a rearward shell while idling above and in cooperative relation with the surface of the rear drum, a knife normally positioned between the drums and below a web winding on the drums, means for reciprocating the knife upwardly into contact with the web to cut the web, resilient means for applying pressure to the pivotal support of the rear shell in addition to any pressure applied by the weight of the parts to increase the rolling pressure of the idling rear shell on the rear drum, and means coordinating with the raising of the knife for actuating the means for applying additional pressure to the rear shell.

20. In a cloth winder, a horizontal rotatable drum, a pair of jaw arms, pivotally supported above the drum on an axis parallel to the drum axis, the jaw arms having at their lower ends jaw portions adapted to pivot a shell on a drum and one of the jaw arms having a lower swingable latch portion, pivotally mounted on the jaw arm and adapted to release the shell pivot, and fluid means operatively connected to the jaw arms and to the latch portion and when energized raising the jaw arms and opening the latch portion, whereby a shell pivoted in the jaws is discharged.

21. In a cloth winder, a drum pivotally mounted on a horizontal axis, a pair of pivoted jaw arms extending over the drum and movable up and down with respect to the drum, stationary jaw portions on the lower ends of the jaw arms, a movable jaw portion pivotally mounted on the lower side on one of the jaw arms, the stationary jaw portions and the movable jaw portion cooperating to pivot a shell on the drum, 10 cam means including an upwardly opening latch for holding the movable jaw portion locked closed, and fluid means operatively connected to the jaw arms and to the movable jaw portion and the cam means for raising the jaw arms and 15 opening the movable jaw portion.
